UNITED STATES PATENT OFFICE.

EL'LOUISE JAMERSON, OF NEW YORK, N. Y.

SEWING-RECEPTACLE.

1,001,645.

Specification of Letters Patent. Patented Aug. 29, 1911.

Application filed July 19, 1910. Serial No. 572,741.

To all whom it may concern:

Be it known that I, EL'LOUISE JAMERSON, a citizen of the United States, residing at New York, in the county and State of New York, have invented a new and useful Improvement in Sewing-Receptacles, of which the following is a specification.

This invention relates to sewing receptacles for use with sewing machines and similar relations where there is a table or supporting shelf or frame to which the bag or receptacle may be detachably secured and held, either in an operative or in a folded up and out of the way position.

The present invention consists primarily in a folding frame and bag adapted to satisfy the foregoing purposes, and comprising a strong, simple structure which can be completely taken apart and packed in a very small compass for shipment, etc., but which can be easily put together in a perfectly secure and rigid manner for use.

In another aspect the invention consists in a structure which is not only adapted to be completely taken apart for package and shipment, as above provided for, but it is also adapted to be folded readily out of any obstructing or conspicuous relation when not in actual use, although fixedly attached for use to the sewing machine or other place when it is to be employed.

Another object of the invention consists in providing a frame made out of cheap strap iron, stamped and fitted with studs in a press, by an arrangement adapted to provide a secure and fixed engagement between the component parts.

Still further objects of the invention will later appear and arise from the features of construction and combination hereinafter described and claimed.

In the drawings, Figure 1, is a perspective view of a "sewing receptacle" embodying the principles of my invention; Fig. 2, is a side elevation with the bag removed; Fig. 3, is a detail top view of part of the frame; Fig. 4, is a detail sectional view of part of the frame, and Fig. 5, is a view from the opposite side of the same.

Referring to the drawings, 1 designates brackets adapted to be fixed in pairs to the under side of a sewing machine table or other similar relation. I make the brackets 1 in such a form as to depend for some distance vertically below the shelf or table to which they are attached, in which relation

these brackets virtually constitute rigid depending posts on the under side of said table.

2 designates a loop-shaped frame pivoted to the posts 1 so as to swing either outward into a horizontal position as shown, or downwardly into a position alongside the posts 1, where it is substantially out of the way.

3 denotes struts which may be engaged to the lower ends of the posts 1 and to portions of the loop-shaped frame 2 so as to prop and sustain the said frame in its horizontal relation. The struts 3 are also most conveniently adapted to fold downward about a permanent pivotal connection 4 at the lower ends of the posts 1, so as to be out of the way when the device is out of use. The connection of the struts 3 with the loop-frame 2 is made detachable for this purpose, and I prefer the key-hole slot and pin engagement 5, 6, as the most desirable fastening for the purpose.

The loop-frame 2 is designed to receive a bag, carrier, or receptacle 7 which constitutes the sewing receptacle proper. I prefer to hem the upper edge of the bag through a length corresponding to about three sides thereof, as shown, and thread the loop-frame 2 through this hem or pocket, thereby concealing the said frame and effectively supporting the bag. In this case the loop-frame 2 should have prongs or hooks 8 which may be integrally stamped thereon so as to catch in the cloth of the bag and hold it in stretched position on the loop-frame. The bag will of course be provided with holes through which the studs 6 may project.

The foregoing provides a bag or receptacle conveniently adapted to be detachably secured and held to a supporting table or shelf, and which may be quickly put in a folded up and out of the way position. This arrangement is light, strong, and compact, and of pleasing appearance, and has many obvious advantages. In addition to the foregoing, however, I make the frame 2 in such a way that it may be taken entirely apart and disassociated from the posts 1. The bag 7 is at the same time adapted to be separated from the frame so that the entire appliance may be packed away in a compact compass.

I make the loop-frame 2 with side-sections 2^a and an end-section 2^b which may

both be of flat bar or strap iron. The side sections 2^a are bent over into L shape at the ends 2^c, and on each such L extension and immediately adjacent to the corner thereof I 5 provide a stud 10. This stud has a head larger than the diameter of its body and is adapted to enter a hole 11 near the end of the piece 2^b, so that said piece may be engaged under the head of the stud, as clearly 10 shown in Fig. 5. 12 denotes a similar stud on the piece 2^b and farther in from the end thereof. This stud engages a slot 13 on the L extension 2^c, the curve of said slot being generally concentric with the stud 10 so that 15 the latter may be engaged with its hole 11 first, and the stud 12 then put in engagement with its slot 13 by an angular movement between the sections 2^a and 2^b, centered about the stud 10. The extensions 2^c 20 are sufficiently projecting to be grasped by the hem of the bag 7 and thus hold the part firmly in said engagement. The hem of the receptacle 7 forms a tubular envelop or pocket which closely incases the extensions 25 2^c thus in effect splicing them to the end member 2^b and preventing any swiveling movement about the stud 10. Inasmuch as 30 no dislodgment of the end member 2^b can take place with respect to the side member 2^a without swiveling about the stud 10, it is evident that the parts are tightly locked against dislodgment. The connections of 35 the sections 2^a with posts 1 also serve the same purpose, as do the connections of the struts 3 with the sections 2^a. Accordingly in use the loop-frame is as rigid as if made in one integral piece.

As a secure and detachable pivotal connection between the loop-frame 2 and the 40 post 1, I prefer to form the inner ends of the loop-frame 2 with vertical slots 14 which may have laterally and backwardly directed inner portions if desired.

15 designates studs on the posts 1 closely 45 adjacent to the upper ends of the same, which studs are adapted to fit in the slots 14. The end of each bar 2^a is curved generally concentric to the stud 15 in its engaged relation with the bar, so that the 50 latter may be swung through half a turn about said stud when the post or bar are to be disengaged from one another. I prefer to employ this arrangement, making the posts with upper end flanges 16, so that in 55 normal use the loop-frame is locked to the

posts throughout the range of the normal pivotal movement. The flanges 16 are also adapted to serve as a means of attachment of the posts to the frame of the sewing machine, or the like, being provided with 60 screw-holes 17 for this purpose.

In practice I make the posts 1, the straps 3, and the various parts of the loop-frame 2, of flat metallic strips of uniform character, and all the parts are adapted to be 65 quickly stamped or formed up in a die press. The posts 1 are made of two similar sections which, however, are permanently 70 fixed together by the pivot pin 4 and the stud 15 at the respective ends, and additional rivets or fastening means may be employed if desired.

In normal use the device is assembled in the manner clearly shown in Fig. 1. When temporarily put out of use the studs 6 are 75 unbuttoned from their key-hole slots 5, after which the loop-frame 2 and the struts 3 are both swung down and out of the way. The device can, whenever desired, be completely 80 taken apart in the manner already described. 80

What I claim is:—

A sewing receptacle comprising the combination of a loop-frame having an end section and entirely separate L shaped side sections, said L-shaped side sections having 85 a pin and a curved slot on their bent ends and said end section having a hole and a pin at each end and co-operating with the pins and slots of the side sections, posts supported wholly from beneath a table or 90 supporting surface and projecting freely but rigidly downward therefrom, pivot pins for permanently connecting said posts and side sections, and struts pivoted to said posts and having key hole slots whereby they are 95 adapted to be detachably secured to said side sections, and a bag having a hemmed pocket at its upper edge constituting a closely fitting tubular casing embracing the overlapping portions of said end and side 100 sections, whereby these are closely bound together, substantially as described.

In testimony whereof, I have signed my name to this specification in the presence of two subscribing witnesses, this 13th day of 105 June 1910.

EL'LOUISE JAMERSON.
